COMBINATION PORTABLE CAR CONSOLE AND ARM REST

John A. Gale, Wayzata, Minn., assignor to Child's Play Products, Inc., Willmar, Minn., a corporation of Minnesota

Filed Aug. 10, 1964, Ser. No. 81,209

Term of patent 14 years

(Cl. D14—6)

FIG. 1

FIG. 2

FIG. 3

FIG. 5

FIG. 4

FIGURE 1 is a perspective view of the combination portable car console and arm rest, showing my new design with the top closed;

FIGURE 2 is a similar perspective view showing the combination portable car console and arm rest with the top open;

I claim:

The ornamental design for a combination portable car console and arm rest, as shown and described.
